Primary Examiner — Mark A Goodwin*(74) Attorney, Agent, or Firm* — Novick, Kim & Lee, PLLC; Jae Youn Kim; Hyun Woo Shin(57) **CLAIM**

We claim the ornamental design for a rubber track, as shown and described.

DESCRIPTION

FIG. 1 is a front, top, left side perspective view of a Rubber Track, showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a front, top, right side perspective view thereof;

FIG. 9 is a rear, top, left side perspective view thereof; and,

FIG. 10 is another front, top, left side perspective view thereof.
